NECKTIE MANUFACTURE

Nathaniel Miller, Baltimore, Md.

Application April 9, 1956, Serial No. 576,853

5 Claims. (Cl. 2—146)

This invention relates to necktie manufacturing and it is more particularly concerned with neckties of the multiple fold type.

A multiple fold necktie, typically, comprises essentially a blank of cloth folded lengthwise to provide four layers of material and stitches to hold the tie in shape.

Such a necktie has numerous advantages over other conventional types of neckties. In the first place, it requires no lining, because it has an adequate build up of body by virtue of the multiple folds, even more than some types of neckties that are provided with linings. Such a mono-material necktie is desirable also because of the fact that it can be washed or cleaned without distortion.

Neckties which utilize a lining are subject to differential shrinking as between the lining and the remaining part of the necktie, because different materials have different coefficients of shrinkage. This may, and frequently does, occur during washing and/or dry cleaning operations. It may also result from humid atmospheric conditions. It is not uncommon to see a necktie out of shape that has never been cleaned or washed, simply because of the differential shrinkage which occurred as between the lining and the necktie material on a humid day.

One attempt to correct this undesirable situation was to make a necktie of a polyester material and use a lining for it that was also of a polyester material. However, even in such cases where some differences might exist between the lining and the body materials of the necktie, such as in the weave, the type of polyester material, etc., some differential shrinkage sometimes occurs.

However, neckties made in accordance with the present invention have all their parts of exactly the same material and, therefore, no possibility of differential shrinkage can take place, regardless of what is used to clean the neckties or how many times they are cleaned or what the humidity conditions may be. The shrinkage is absolutely uniform throughout.

Multiple ply mono-material neckties of this type, however, have not found complete favor heretofore in the trade because of their high cost of manufacture. Prior to the present invention, such neckties were manufactured by first forming a blank, then creasing the blank along three longitudinal lines, spaced from each other, then folding the blank along the creased lines, applying stitches, customarily bar stitches, and reversing the tubular form thus developed. This general method of manufacture is slow and expensive because of the time consuming requirement to apply the longitudinal creases to each blank. In some cases, machines have been developed for applying these creases to a multiple number of blanks, but they usually are able to handle only about 6 to 12 blanks at a time, being on the order of a steam pressing apparatus with special crease-forming dies. See U.S. Patent No. 2,441,654. However, the creases are not always uniform as among the different blanks of a group because of the layers of material placed in the dies, and the use of the machine in other respects involves many other variations among the blanks which, in addition to the high cost of

2

the creasing machine as a tool, makes it an unsatisfactory operation.

The general object of the present invention is the provision of a method of manufacturing multiple fold mono-material neckties of the type mentioned which is simple, efficient, and which does not require the use of any special machinery, other than that generally used in the clothing manufacturing industry.

Another object of the invention is the provision of such a method which requires no precreasing of the blanks from which the neckties are made, and hence requires none of the expensive creasing machinery heretofore used.

A still further object of the invention is the provision of such a method which is not limited by such bottle necks as creasing operations and others incident thereto, such as the special handling required therefor.

These and other objects, features, and advantages of the invention will appear more fully from the following description considered together with the accompanying drawing.

In the drawing:

Fig. 1 is a top plan view of a cutting table, partly broken away, containing a pile of sheets of fabric overlaid by a cutting and drilling pattern in accordance with the invention.

Fig. 2 is a side elevational view, also partly in section, of the same cutting table in conjunction with a drilling tool that may be used in the method of this invention.

Fig. 3 is a fragmentary sectional view of a portion of the same cutting table on a somewhat larger scale.

Fig. 4 is a plan view of two complementary blank sections resulting from the cutting and drilling operations, joined together to form a complete two-piece blank.

Fig. 5 is a plan view of a complete blank after it has been folded along the longitudinal center and secured in accordance with this invention.

Fig. 6 is a plan view of a completed necktie resulting from a reversing of the sewed blank of Fig. 5.

Fig. 7 is a rear face view of a portion of the larger end of the completed necktie, partly broken away.

Fig. 8 is a rear face view of a portion of the smaller end of the completed necktie, partly broken away.

Fig. 9 is a section along the line 9—9 of Fig. 6 on a larger scale.

Fig. 10 is a section along the line 10—10 of Fig. 5 on a larger scale.

Referring with more particularity to the drawing in which like numerals designate like parts, the method of this invention comprises, generally, the steps of first laying up a number of sheets of fabric 11 from which a number of neckties are to be made, on a cutting table 12. The sheets of fabric may number as many as 250 to 400 or more, as is customary on cutting tables of the clothing industry generally.

Overlaid on the pile of sheets is a pattern or templet 13 containing the cutting lines 14 for forming the large end blank section pattern 15, and cutting lines 16 forming the small end blank section pattern 17. The templet 13 also contains, in accordance with this invention, lines of dots 18 and 19 for drilling index holes, hereinafter more fully explained.

The holes are preferably drilled first before the blanks are cut out along the lines 14 and 16, because it is easier to maintain the larger sheets of fabric in alignment for this purpose than the smaller blank pieces. However, it is to be understood that either operation may be performed first within the scope of this invention. The holes are drilled completely through the pile of fabric sheets by an electric drill 20 having as its drill element a long thin needle 21. This needle may be solid for those types of fabric which retain clearly and visibly the shape of a hole drilled therein. However, there are

other types of fabrics which, because of their compositions, weave, texture, design, or for other reasons, do not retain such a clear and visible hole after drilling, and in such cases, the needle, as shown in the drawing, should be hollow with an outlet 22 near the bottom for the discharge of a fluid as the needle passes through the fabric pile. The fluid contains in solution or suspension any of the numerous known types of material which are luminous under ultra-violet light, or as it is sometimes called, "black light," but which are non-luminous under ordinary sunlight. This type of drill and liquid materials used therewith are in general use in the clothing industry. Such a drill is manufactured and sold under the name "Drill-Marker" by Beaver Cloth Cutting Machines, Inc., of New York, N.Y., and is described in U.S. Patent No. 2,778,297. Fluorescent liquids suitable for use therewith are well known, a few of which are described in U.S. Patents Nos. 2,056,809, 2,482,450 and 2,267,758.

The resulting holes 23 and 24 thus drilled are along lines in the formed blank sections 25 and 26, respectively, and they are approximately $\frac{1}{4}$ the distance from one of the lateral edges thereof.

Between the top of the table 12 and the lowermost layer or sheet of cloth 27 of the pile 11, a piece of cardboard 28 is interposed having a thickness equal to at least the distance between the point 29 of the needle and the outlet 22, so that the bottommost sheets of fabric will be treated with the fluid as well as the others.

After the holes 23 and 24 have been drilled, the blank sections are cut out with any ordinary cloth cutting tool (not shown) which is well known in the clothing manufacturing art. Complementary blank sections 25 and 26 are then sewed together at their inner ends 30 and 31 to form a complete two-piece blank 32. It is to be understood, however, that the invention is equally applicable to those cases where complete one-piece blanks are initially cut from the fabric materials.

The complete blank 32 is then folded in half longitudinally with its outer longitudinal edges 33 and 34 in registry, the fold line being indicated by the numeral 35. The two superimposed halves are then sewed together with a line of stitching 36 indexed by the lines of drilled holes 23 and 24 which fall in contiguous relation to each other when the two blank sections are sewed together, along the line of holes or on either side thereof, but preferably on the side thereof facing the fold line 35. If the holes cannot be distinguished otherwise, they may be placed under ultra-violet light during the sewing operation, whereupon they will become brilliantly luminescent.

Thus, a tube is formed with the "right" side of the material on the inside of the tube. By then merely reversing the tube thus formed, that is, turning it inside out, a common procedure used in the necktie manufacturing industry, with the usual necktie reversing apparatus (not shown, but see U.S. Patent No. 2,378,671), the necktie is completed. It may then be pressed, labeled, and boxed in accordance with the usual practice.

Having thus described my invention, I claim:

1. The method of manufacturing a multiplicity of multiple fold neckties comprising laying up a stack of cloth sheets from which the neckties are to be made, each sheet of the stack being of a size to itself yield a plurality of neckties, placing on top of the stack a pattern of guide lines delineating the boundaries of elongated

gated complementary blank sections from which the neckties are to be made and reference marks within the boundaries of the sections, said reference marks each being disposed in a line longitudinally of a blank section and substantially one-fourth the distance between the longitudinal edges of the section, piercing the entire stack of sheets simultaneously with rows of holes beneath said reference marks, cutting the entire pile of sheets simultaneously along lines below the said guide lines to separate the blank sections with the pierced holes therethrough, then sewing together complementary blank sections to form in each case a complete elongated necktie blank, folding each complete blank in half lengthwise with the longitudinal edges thereof in substantial registry and securing the folded halves together with stitches extending longitudinally along a line adjacent the pierced holes to form a tubular piece with exterior longitudinal flaps, and then reversing the resulting tubular piece, thereby disposing the said flaps on the interior of the tubular piece and providing a necktie with multiple folds.

2. A method as defined by claim 1 in which the step of piercing the sheets with holes is effected prior to the step of cutting the sheets along lines below the guide lines, whereby relative displacement of the sections during the piercing operation is substantially obviated.

3. The method as defined by claim 1 in which the holes are formed in the sheets by drilling and a luminous liquid substance is deposited in each hole simultaneously with the drilling thereof.

4. The method as defined by claim 3 in which the luminous material is luminous under a special kind of light only, other than sunlight, and the step of sewing the folded halves of the blank together is performed in the presence of such special light.

5. The method of manufacturing a multiplicity of multiple fold neckties comprising laying up a stack of cloth sheets from which the neckties are to be made, each sheet of the stack being of a size to itself yield a plurality of neckties, placing on top of the stack a pattern of guide lines delineating the boundaries of elongated blanks from which the neckties are to be made and reference marks within the boundaries of the blanks, said reference marks each being disposed in a line longitudinally of a blank and substantially one-fourth the distance between the longitudinal edges of the blank, piercing the entire stack of sheets simultaneously with rows of holes beneath said reference marks, cutting the entire pile of sheets simultaneously along lines below the said guide lines to separate the blanks with the pierced holes therethrough, folding each blank in half lengthwise with the longitudinal edges thereof in substantial registry and securing the folded halves together with stitches extending longitudinally along a line adjacent the pierced holes to form a tubular piece with exterior longitudinal flaps, and then reversing the resulting tubular piece, thereby disposing the said flaps on the interior of the tubular piece and providing a necktie with multiple folds.
